CURB STOP BOX

Fred C. Le Duc, Minneapolis, Minn., assignor, by
mesne assignments, to Western Metal Products
Company, a corporation of Minnesota

Application February 13, 1932, Serial No. 592,732

2 Claims. (Cl. 137—13)

This invention relates to curb stop boxes for municipal water and gas mains. These curb stop boxes are used in great numbers by municipalities, gas and water companies, and it is essential that the original cost of these curb stop boxes be small and that the curb stop boxes be so constructed that they may be maintained in use for long periods of time without necessitating expensive replacement of parts.

10 It is an object of this invention therefore, to provide a novel curb stop box which is inexpensive in original installation and which can be used for long periods of time without necessitating digging up the box and without necessitating expensive replacement of parts of the box.

15 It is another object to provide a curb stop fitting so constructed that it will prevent the weight of the entire stop box from falling on the water or gas main in connection with which it is used.

20 Yet another object is to provide a fitting which will embrace the connector shoulders of a curb stop valve to hold the same as a wrench, and thereby prevent injury to the curb stop valve or to the connections between the water or gas main and the curb stop valve when the stop box is in use.

25 A further object is to prevent the passage of dirt either upwardly from the curb stop fitting to the main portion of the stop box above the same, or from the main portion of the stop box to the fitting while permitting drainage of water from the main portion of the stop box through the fitting.

30 These and other objects and advantages of the present invention will more fully appear from the following description, made in connection with the accompanying drawing, wherein like reference characters refer to the same or similar parts throughout the various views, and, in which,

35 Fig. 1 is a vertical section taken through a complete stop box installation, the stop box embodying the present invention being illustrated;

40 Fig. 2 is a plan view of the curb stop fitting, the curb stop valve and the apertured disk taken substantially on the line 2—2 of Fig. 1;

45 Fig. 3 is a vertical section taken on the line 3—3 of Fig. 1;

Fig. 4 is a plan view of the head of the box;

50 Fig. 5 is a plan view of the apertured disk used; and

Fig. 6 is a vertical section through the disk taken on the line 6—6 of Fig. 5, as indicated by the arrows.

55 Referring to the drawing, there are illustrated portions of two pipe sections 7 and 7a of a wa-

ter or gas line and these pipe sections are connected to a curb stop valve 8 having a flat bottom and polygonal-shaped shoulders 8a. One of the shoulders 8a is tapped to receive an end of the pipe section 7, while the other shoulder is provided with a projecting nipple 8b to which is connected a reducer sleeve 7b within which an end of the pipe section 7a is received. The end of the nipple 8b is beveled as shown and the extreme end of the pipe section 7a is outwardly flared to bear against the beveled end of the nipple when the reducer sleeve is drawn tightly on to the nipple. The pipe section 7a is of bronze and of the type now commonly employed as a lead in pipe from a water main to a dwelling or other building. The joint formed between the pipe sections 7a and the curb stop valve 8 is one upon which undue strain cannot be placed without danger of opening the joint. The curb stop valve 8 has an upwardly projecting cylindrical portion 8b through which the stem 8c of the valve fits. The valve is shown as having a flange 8d below the cylindrical portion 8b. The curb stop valve illustrated is a simple and inexpensive type now commonly employed and the joint between the valve and the pipe section 7a is also now commonly used.

55 In accordance with the present invention, there is provided a curb stop fitting 9 within which the curb stop valve 8 is received. This fitting 9 has a closed lower end and upwardly projecting cylindrical side walls which terminate in outwardly extending segmental flanges 9a apertured to receive nutted bolts 10. The bottom of the fitting projects outwardly from the side walls thereof to form a flange 9b, opposite portions of the edges of which are arcuate in shape and other opposite portions of the edges of which are parallel, as best shown in Fig. 2. The fitting is, of course, open at its upper end. Vertical slots 11 are formed in the side walls of the fitting 9 and these slots are diametrically oppositely opposed and they run from the upper edge of the side walls of the fitting downwardly for a distance greater than the diameter of the tapped connector shoulders of the curb stop valve 8 adapted to be received within the fitting. The width of the slots 11 corresponds to the transverse width of the connector shoulders 8a of the valve. To receive the connector shoulders 8a, the lower ends of the slots are shaped to correspond in configuration to the lower portions of the polygonal-shaped shoulders 8a, as best shown in Fig. 3. The curb stop valve 8 fits within the fitting 9 with the shoulders 8a projecting through the slots 11, as shown.

and the edges of the walls of the fitting adjacent the slots 11 bear against the polygonal-shaped connector shoulders 8a of the curb stop valve to hold the valve as a wrench while at the same time limited relative vertical movement between the fitting and valve is permitted. After the curb stop valve is placed within the fitting 9, the fitting is filled with packing material 12 such as oakum to fill the space in the fitting not occupied by the curb stop valve. This packing material is, of course, resilient and does not interfere with vertical movement of the fitting relative to the valve.

An apertured disk 13 closes the opening at the top of the fitting 9 and has a projecting flange 13a at its top which rests on the upper edge of the walls of the fitting. The cylindrical portion 3b projects upwardly through the aperture of the disk 13 and the disk serves to center the stop valve 8 within fitting 9. The lower pipe section 14 of a pair of telescoping pipe sections 14 and 15 respectively, rests on the upper flanged end of the curb stop fitting 9 and has an outturned flange at its lower end secured to the flanges 9a of the fitting by means of the nutted bolts 10. It should perhaps be here mentioned that the nutted bolts 10 are constructed of bronze or some similar material which will not rust. The lower end of the lower pipe section 14 is internally rabbeted as shown in Fig. 1, to receive the flange 13a of the apertured disk 13 and it will thus be seen that the disk 13 prevents relative movement between the pipe section 14 and the curb stop fitting 9. The upper portion of the lower pipe section 14 is narrowed as illustrated, and at its upper end the lower section is provided with a grooved head in which is seated a cushion treated packing gland 16 for maintaining a tight joint between the lower section 14 and the upper section 15 which is received within the lower section.

Secured to the upper end of the upper section 15 adjacent the ground level is a housing composed of several parts. The main or body portion of this housing consists of a head 17 having a bottom from which extends a downwardly projecting sleeve like portion 17a screw threaded to receive the upper end of the upper pipe section 15. A vertical flange rises from the edges of the bottom of the head 17. The bottom of the head 17 has a central circular aperture therein immediately above the upper pipe section 15 and the walls 17b of the head adjacent this aperture flare upwardly and outwardly to receive and support a nut 18 shaped to fit the aperture and having upwardly and outwardly flaring walls 18a. The vertical flange of the head 17 is provided with a recess 17c extending into the flange from the inner side thereof and within this recess is received a lug 18b projecting from the body of the nut 18. A cover 19 rests within the vertical flange of the head 17 upon the nut 18 and the bottom of the head and this cover has a projecting lug 19a which fits within a second recess 17b in the vertical flange of the head above and diametrically opposed from the recess 17c. The nut 18 has a central tapped opening, while an opening is formed in the cover 19 above the opening in the nut. A bolt 20 has a polygonal-shaped head received within a recess within the top of the cover 19 and this bolt projects through the opening in the cover 19 and has screw-threaded engagement with the tapped opening in the nut 18. The nut 18 and the bolt 20 are preferably formed of bronze or similar rust resisting material. Preferably above the lug 19a of the cover,

the cover is provided with a straight surface which engages with a straight surface formed at the inner side of the flange of the head 17.

The two telescoping pipe sections 14 and 15 of the stop box permit adjustment of the length of the stop box to meet varying conditions. As the portions of the curb stop fitting 9 adjacent the connector shoulders 8a of the curb stop valve, hold the curb stop valve as a wrench, the curb stop valve cannot be sprung as the pipe sections 14 and 15 are connected thereto and as the valve stem 8c of the valve is turned, no strain will be imposed upon the pipe sections 14 or 15 to tend to loosen the connections between these pipe sections and the curb stop valve. When the fitting 9 is first inserted in place, it will be located as shown in Fig. 1 with the connector shoulder 8a of the curb stop valve 8 disposed within the lower portions of the slots 11. In this position it will be seen that the weight of the stop box is not imposed upon the curb stop valve or the water or gas line. As the dirt about the fitting settles, the entire curb stop box or, at least, that portion of the same from the lower pipe section 14 downwardly may move downwardly relative to the curb stop valve 8 without imposing the weight of the curb stop box upon the curb stop valve or line. The slots 11 permit this movement.

The apertured disk 13 in addition to centering the curb stop valve in the fitting 9 and preventing relative movement between the fitting and the lower pipe section 15, prevents the passage of dirt downwardly from the lower pipe section 14 to the fitting 9, while permitting the drainage of water from the lower pipe section 14 to the fitting and it also prevents the passage of dirt upwardly from the fitting 9 to the lower pipe section 15. As the fitting 9 is closed at its lower end, dirt cannot accumulate between the bottom of the curb stop valve and the lower end of the fitting to prevent proper operation of the valve. As the flange 9b of the fitting has edges which are partly curved and partly straight, and as the flanges 9a and the lower flange of the lower section 14 are not truly circular in contour, it will be seen that there will be no tendency for the curb stop box to turn in the ground as the valve stem 8c is turned. It should be mentioned that a small opening 9c is provided in the lower portion of the vertical wall of the fitting to permit drainage of water therefrom.

By provision of the nut 18 engaging with the bolt 20, it is seen that the housing at the top of the stop box may be effectively closed without using a bolt which is screw threaded in either the head 17 or the cover 19. As the bolt 20 and nut 18 are composed of bronze, there is no tendency for these parts to rust together after continued usage. If the threads in the nut 18 or on the bolt 20 become damaged at any time, either or both of these parts can be replaced with but slight expense without necessitating replacement of either head 17 or cover 19.

It will be seen that an extremely simple, inexpensive and efficient curb stop box has been provided.

It will, of course, be understood that various changes may be made in the form, details, arrangements and proportions of the various parts without departing from the scope of the present invention, which generally stated consists in the matter shown and described and defined in the appended claims.

What is claimed is:—

1. The combination with a curb stop box, of a curb stop fitting having an open upper end connected to said box and adapted to receive a curb stop valve therein, an apertured disk mounted and held from movement between the upper end of said fitting and said box and through the aperture in which the curb stop valve is adapted to project, said disk acting to center the curb stop valve in the fitting and to prevent the passage of dirt either upwardly from said fitting to said box or downwardly from said box to said fitting and at the same time permitting water to drain from said box into said fitting.
2. The combination with a curb stop box, of a curb stop fitting comprising a casing closed at its lower end and open at its upper end, said casing being adapted to receive a curb stop valve having polygonal-shaped connector shoulders, said casing being slotted from its upper end downwardly at diametrically opposite points to receive and hold as a wrench the polygonal-shaped connector shoulders of the curb stop valve, said slots being of such length as to permit of limited relative vertical movement between said fitting and said curb stop valve, an apertured disk resting upon the upper portion of said curb stop fitting and adapted to encircle the upper portion of the curb stop valve to form a closure for the upper portion of said fitting, and a curb stop box secured to the upper end of said fitting said fitting and box including means preventing movement of said disk upwardly and downwardly relative to said fitting.
